FIGURATOR

Jacob Reese

UNITED STATES PATENT OFFICE.

JACOB REESE, OF PITTSBURG, PENNSYLVANIA.

ROLLS FOR REDUCING OLD RAILS TO ANGLE-BARS.

SPECIFICATION forming part of Letters Patent No. 371,359, dated October 11, 1887.

Application filed February 18, 1884. Serial No. 121,234. (No model.)

To all whom it may concern:

Be it known that I, JACOB REESE, a citizen of the United States, and a resident of Pittsburgh, in the county of Allegheny and State of Pennsylvania, have invented a certain new and useful Improvement in the Utilization of Old Rails in the Manufacture of Angle Shapes; and I do hereby declare the following to be a full, clear, and exact description thereof, reference being had to the accompanying drawings, in which—

Figure 1 indicates a front elevation of a set of rolls provided with a series of grooves adapted to reduce the flange and web of the rail into a finished angle-bar. Fig. 2 indicates a front elevation of a set of rolls provided with a series of suitable grooves for reducing the flange and web of a rail into finished angle fish-plates. Fig. 3 indicates an end view of the web and flange of a rail as slit from the head previous to subjecting the metal to the rolling operation. Fig. 4 indicates an end view of a set of finished angle fish-plates adjusted on a rail indicating the mode of fastening the former to the latter.

Angle shapes have heretofore been rolled out of blooms, billets, and piles; but in my present invention I propose to produce them from old rails. The characteristic features of the invention, therefore, are, the web and flange of the rail are subjected to the reducing action of a series of passes, which are so arranged as to force down one side of the flange and distribute the displaced metal into the other portion of the blank, thus producing an angle-blank, which is then reduced by subsequent passes into the finished size, shape, or form desired. Both sides of ordinary angle-shapes are made of the same width. In such manufacture I therefore propose to ordinarily slit the head off of the rail previous to subjecting the metal to the rolling operation, as such a mode of procedure gives an initial blank, which requires but little redistribution of metal to bring it to the form desired. In such manufacture the old rails are heated to a temperature of about 1,500° Fahrenheit, and slit, as shown by Fig. 3, which may be done by means of the machine patented to me in Patent No. 7,680, of May 15, 1877. The web and flange or rail-blank is then passed through the grooved

rolls (shown in Fig. 1) until the metal is reduced to the desired form. In this operation the action of the first pass, A, reduces the metal in the upper side of the flange and forces it down, deepening and thickening the lower or opposite side. This action is repeated by the second pass in the groove B, and also in the third or C pass, by which time the blank assumes a rough angle form. The remaining passes are of ordinary character, and bring the angle-blank to the finished form in the usual manner.

By this method steel angle shapes of all sizes from four by four to two by two inches may be made; but when smaller angles are desired it is necessary to pass the angle-blank through ordinary angle edging grooves, as will be readily understood by those familiar with rolling operations. When larger sizes are wanted—for instance, such as four by six or four by seven inches—I do not slit the head from the rail, but retain it to give more metal to form the larger or widest side of the angle. In this case it is necessary to construct the rolls with suitable grooves for rolling the web and head into one side of the angle and roll the flange down into the other side.

In Fig. 2 a set of rolls is shown similar to those of the preceding figure, except the last groove, E, is of the peculiar form used to form the angle-blank into the required shape for angle fish-plates.

It is advisable to turn up the grooves for reducing one side of the flange—that is, the grooves A, B, and C—so that room may be had to allow the metal to flow laterally into the web, as a tendency to a greater or less amount of lateral flow will exist during this part of the operation, and it can be provided for without taking too much metal from the flange.

The advantages of utilizing old rails in the manufacture of iron and steel angle shapes are, first, old steel rails are now selling at twenty-three dollars per ton, while steel blooms and billets are worth from thirty-five to forty dollars; second, the rails may be rolled into steel angles at less cost of labor and with less expenditure of power than required when blooms and billets are used; third, the capacity of the mill is largely increased, as less reduction is necessary, so that indirectly all incidental ex-

penses are lowered and greater economy of manufacture is secured; and, finally, when slit rails are used, the rail-heads are worth as billets five dollars more per ton than the price of old rails.

Having described my invention, what I claim, and desire to secure by Letters Patent, is—

The rolls having the passes, the first approximating to the shape of a rail, the last to the shape of an angle-bar, and the intervening passes shaped substantially as described.

JACOB REESE.
